UNITED STATES PATENT OFFICE.

EDWARD H. ANGLE, OF MINNEAPOLIS, MINNESOTA.

DENTAL TOOTH-REGULATING SCREW.

SPECIFICATION forming part of Letters Patent No. 399,177, dated March 5, 1889.

Application filed February 18, 1888. Serial No. 264,531. (No model.)

To all whom it may concern:

Be it known that I, EDWARD H. ANGLE, a citizen of the United States, and a resident of the city of Minneapolis, county of Hennepin, 5 State of Minnesota, have invented a certain new and useful Regulating Device for use in Dentistry, of which the following is a specification, reference being had to the accompanying drawings.

10 My invention relates to dentistry, and has for its object to provide an efficient device for regulating the teeth, which shall at the same time be simple in construction, easy of application, cleanly, and cause a minimum of discomfort to the patient. Its construction is hereinafter fully described, and particularly 15 pointed out in the claim.

In the drawings, like letters referring to like parts, Figure 1 is a plan view of part of 20 the human jaw, showing my device in working position to accomplish one class of movements possible by the device. Fig. 2 is a side view of the same, showing part of the jaw cut away, illustrating the device as applied to 25 draw a tooth backward in the line of the arch. Fig. 3 is a plan view of part of the human jaw with the device in working position to accomplish another class of movements possible by the device to push a tooth outward, 30 and Fig. 4 is a side view of the same, showing part of the jaw cut away that the working and effect of the device as applied in Fig. 3 may be better shown.

The device is composed of a screw-threaded 35 shaft, A, provided with a right-angled extremity, a, a short tubular sheath or resistance-tube, B, of smooth bore and open at both ends, within which tube said delivery-shaft A accurately fits and may pass in either direction, a screw-threaded nut, C, fitting said delivery shaft A, and which nut may be applied on said shaft at either end of the tube B, and thus either push or pull said shaft through said tube, a short delivery-tube, D, 40 adapted to receive the right-angled extremity a, and suitable bands, E and F, for attaching said tubes B and D to the teeth, the tube B being rigidly soldered to the band or bands E, and the tube D being soldered to the 45 band F.

The bands E and F, previously made of proper size, are tightly cemented to the teeth.

The shaft A should be rigid and have but little or no spring.

This entire appliance or parts thereof to be 55 made of any suitable metal or metals.

The application is shown in Figs. 1, 2, 3, and 4, wherein G represents a portion of the human jaw, and H, K, K', L, and M represent teeth in the same. Of these the tooth L is 60 represented as out of its normal position in the arch, and it is desirable to draw it backward in Figs. 1 and 2, and push it forward in Figs. 3 and 4 to its proper place in the dental arch. On some firmly-rooted tooth or teeth, 65 as K K', in suitable position with reference to L, is cemented the band or bands E, to which is rigidly soldered the tube B. On the tooth L is cemented the band F, to which is soldered the tube D at right angles to the 70 tooth and the delivery-shaft A. The screw-threaded portion of the delivery-shaft A is passed through the tube B, and the right-angled extremity a is placed in the tube D. The nut C is then applied to the end of the 75 shaft A projecting through the tube B, if used to pull, as in Fig. 1; but if used to push, as in Fig. 3, the nut C is applied to the shaft A before placing in the tube B, and is brought to bear upon the end of the said tube opposite 80 to the end used in pulling. By the proper adjustments from time to time the tooth may be moved to its proper position in the arch.

The especial excellencies of the device, in 85 virtue of its construction and application, are as follows: In accordance with the natural law that action and reaction are equal and opposite in direction, the tooth to be moved, L, and the teeth serving as anchorages, K K', 90 will move equally when equal forces are applied to the same, unless there be greater resistance offered by one than the other by means of more dense surroundings, or by means of such a device as shall prevent movement of the one and promote that of the other. 95 This latter feature I claim to accomplish by my device, as I shall hereinafter point out.

As before stated, the tube B is rigidly soldered to the band or bands E, which are tightly cemented to the teeth, serving as 100 anchorages, K K'. The tube D is soldered in similar manner to the band F, which is cemented to the tooth L to be moved. The shaft A being passed through the tube B,

and the extremity *a* being placed in the tube D and the nut C turned, the tendency would be to move, in directions opposite, both L and K K' at their crowns, while the apices 5 of their roots would remain almost unmoved were it not that the device of the tube B containing the accurately-fitting shaft A does not allow the anchor-teeth K K' to move at their crowns without moving also an equal 10 distance at the apices of their roots, thus being dragged or pushed bodily through the bony surroundings, movement under which condition is rendered well-nigh impossible from the fact that the bone surrounding the 15 apex of the root is much more dense than that surrounding the portions nearer the crown. The tooth L thus practically receives all the force transmitted through the shaft A by the turning of the nut C, and L, being so attached 20 that it may tilt or move freely at its crown, is rapidly moved to its place in the dental arch, while the anchor-teeth K K' either do not move at all or move so little that it is imperceptible, as movement under the conditions 25 in which they must move is nearly or quite impossible. These points are shown in Figs. 2 and 4.

Another point of excellence my device obtains is that in consequence of the extremity 30 *a* of the shaft A being at right angles to the line of movement of said shaft, and fitting accurately into the tube D, rotation of the moving tooth L is impossible. This is shown in Figs. 1 and 3.

The device is also very cleanly, being so 35 constructed as to lodge but little food, and that can be easily removed by ordinary means. The device is also superior in point of simplicity, comfort, and looks. The parts are few and easily made and applied. Being 40 small, they do not greatly encumber or disfigure the mouth. The supreme importance of these points is well understood and appreciated by all practical dentists. To secure adequate resistance without disturbing the 45 anchor-teeth, to prevent rotation of the moving tooth, to prepare an appliance simple, cleanly, and comfortable, have always been points of great difficulty in regulating teeth.

What I claim, and desire to secure by Letters Patent of the United States, is as follows:

The combination, with the resistance-tube and its band adapted to be cemented to the anchor-teeth, of the delivery-tube and its band adapted to be cemented to the tooth to 55 be moved at right angles to the resistance-tube, a screw-threaded shaft having a body adapted to closely fit said resistance-tube and a right-angled extremity adapted to closely fit said delivery-tube, and a screw-threaded 60 nut adapted to fit said screw-threaded shaft and bear against said resistance-tube, substantially as described.

EDWARD H. ANGLE.

In presence of—

CHAS. G. BROWN,
EMMA F. ELMORE.
